UNITED STATES PATENT OFFICE.

FRANK B. WILDMAN AND GEORGE LAWSON BALLARD, OF NORRISTOWN, PENNSYLVANIA, ASSIGNORS TO WILDMAN MFG. CO., A CORPORATION OF PENNSYLVANIA.

TUBULAR-WELT-KNITTING MACHINE.

1,127,334.

Specification of Letters Patent.

Patented Feb. 2, 1915.

Application filed June 18, 1912. Serial No. 704,443.

To all whom it may concern:

Be it known that we, FRANK B. WILDMAN and GEORGE LAWSON BALLARD, a citizen of the United States and a subject of the King of Great Britain, respectively, residing at Norristown, Pennsylvania, have invented certain new and useful improvements in Tubular-Welt-Knitting Machines, of which the following is a specification.

10 19 The invention relates to circular latch needle knitting machines of the cylinder and dial type, and is designed to produce tubular wefts.

15 The invention is shown in connection with a six-feed body machine, though it is not limited in this respect, and it embodies the general principle of operation as is disclosed in Letters Patent of the United States granted to us December 17, 1912, #1,047,355.

20 25 To the drawings Figure 1 is a plan view of a circular knitting machine embodying our invention, some parts being omitted; Fig. 2 is a side view with parts omitted; Fig. 3 is a developed view of a set of cylinder cams; Fig. 4 is a bottom plan view of the dial cap showing the cams for a four feed machine; Fig. 5 is an edge view of a portion of the dial cap; Fig. 6 is a sectional view through a portion of the dial cap on 30 the line 6-6 of Fig. 4; Fig. 7 is a detail view of a catch.

25 30 Cylinder cams.—The cams of the cylinder comprise a plurality of sets each set being like that disclosed in the application above referred to, and consisting (referring to Fig. 3) of a fixed advancing cam 1, an adjustable stitch cam 2, a clearing course cam 3, 4, a cam 5 to lift the cylinder needles into a brush for operating the latches after 40 the stitches have been dropped therefrom at the clearing cam, a cam 6, 6' leaving step by step adjustment automatically to put the cylinder needles out of action, the adjusting post for which cam is shown at 7, and 45 each set of cylinder cams includes a stitch cam 8 which is also adjustable automatically. The cam 6, 6', while the machine is knitting regular rib, answers as an advancing cam. In Fig. 1 we have marked these 50 reference characters on the base of the machine on radii corresponding substantially to the position of the cams.

A set of dial cams comprises an advancing cam 1', in the form of a pivoted wing cam, 55 a stitch cam 2', a second adjustable arcane-

ing or wing cam 6'' and a second stitch cam 8', these being positioned in the dial corresponding to the position of the cams 1, 2, 6-6', and 8 of the cylinder. In a six-feed machine there are three of the sets of dial 60 cams and three of the sets of cylinder cams, described above, and each set, it will be noted, has two advancing and two stitch cams, making thus provision for six feeds. Fig. 4 shows cams for a four feed machine. 65 In knitting rib fabric the cams of the cylinder and dial are in the positions shown in Figs. 3 and 4.

70 For forming the two walled or tubular welt above mentioned, alternate wing or advancing cams 1' of the dial are connected up to be adjusted automatically and in unison from pattern mechanism on the fixed frame and alternate advancing cams of the cylinder, i. e., the three cams 6-6' are connected up to be adjusted in unison from this pattern mechanism, it being observed that those wing cams 1' of the dial which are automatically controlled are opposite or co-operate with those advancing cams 1 of the 75 cylinder which are fixed, while those alternate advancing cams, i. e., 6-6' of the cylinder which are automatically controlled, are adjacent those advancing or wing cams 6'' of the dial which are fixed, or rather, 80 which are not automatically adjustable. In other words, the automatically controlled cams of the dial and cylinder alternate in 85 position in respect to each other, and each lies adjacent the fixed advancing cam of the 90 other set.

95 Operation.—In operation, the alternate wing cams 1' of the dial are thrown into welt position to simply hold the loops without forming new stitches, with the result that at these feeds *a* a welt is formed on the cylinder needles. While this is taking place at these feeds *a* at the alternate feeds *b* regular rib is being produced, their courses alternating with the welt courses formed on 100 the cylinder needles at the feeds *a*. When a sufficient number of welt courses have been knit to prevent raveling back, the clearing course is then made, and this is done by raising the clearing course cams 3 to the 105 position shown in dotted lines, Fig. 3, to get the loops back of the latches to be thrown off when the needles retract. Immediately following the point where the cylinder needles knit off for making the clearing courses, 110

there are the brushes of bristles 4* supported on the dial cap, for opening the latches of the cylinder needles so that they will be open to receive the thread when they arrive at the next feed. Immediately following the clearing action, the cylinder needles are empty until they arrive at the next feed, *i. e.*, the cam 6, 6', where they advance and receive yarn which is to form the foundation of the tubular welt. No stitches are formed at this time, however, on the cylinder needles at this feed *b*, though there are stitches formed on the dial needles, because there are no old loops on the cylinder needles, but the cylinder needles simply receive the thread and this goes on until all the cylinder needles that have been cleared take on the thread, and when this is done, the cams 6, 6', immediately drop out of action, so that no loops will be formed at these feeds on the cylinder needles. The knitting of the plain fabric for one wall of the welt on the cylinder needles begins, however, when the needles arrive at the feeds *a*, and the dial needles begin to knit the other wall of the welt when the cylinder needles are thrown out at the feeds *b* as just described. In other words, the taking on of the thread by the cylinder needles following the clearing course resumes plain knitting on the cylinder needles for one wall of the welt when the cylinder needles arrive at the feeds *a* owing to the wing cam remaining in welt position, and the dial knitting plain fabric for the inner wall of the welt begins at the feeds *b* when the cylinder needles are thrown out of operation.

In throwing the cylinder needles out of operation as just described, the special cam 6, 6' is first moved down from the position shown in Fig. 3 to that shown in dotted lines, Fig. 3, *i. e.*, to the point where the cylinder needles would be tucking, and on the continuation of the revolution when the needles that have been cleared pass the yarn guide on feed *b* the cam is dropped all the way down out of action, and clear of the path of the dial needles, and the welt formation now begins; on the dial needles at this feed and on the cylinder needles when they arrive at the next feed, *i. e.*, feed *a*. The interval between the two downward movements of the cam 6, 6', is to insure that the needles that have been cleared will pass the feed *b* before the cam drops all the way.

All of the cams 6, 6', are controlled from pattern mechanism situated at the left of the machine in Fig. 1. The posts 7 of these cams are operated by arms 9, on rock sleeves 60 or shafts 10 mounted in brackets 11 fixed to the cylinder can ring, the rock sleeves being operated by rods 12 connected to a ring 13 in an annular recess of the dial cap, to be partially rotated by a rod 14 pivoted thereto at 15 and connected with a lever

16 which is controlled by a pattern wheel 17 and by a spring 18. The lever 16 is pivotally mounted in a frame bracket 19, which also has a socket in which the spring 18 is located. The spring presses upwardly on an arm 16' of the lever and the other arm 16'' of the lever carries a roller 16* which bears on the pattern wheel 17. The spring gives the movement to the lever which depresses the cams, the wheel 17 in conjunction with other means now to be described determining when this spring shall exert its force. The first downward step of the cams 6, 6', is due to the pattern wheel in its revolution bringing the low part or vacant space 17* of its pattern surface to the roller of the lever 16, whereupon the spring 18 will move the pattern lever and depress the cams 6, 6' until the pin or arm 20 on one of the rock sleeves engages a catch 21, Figs. 1, 2 and 7, pivoted to the base plate of the head. This will determine the limit of the first step movement of the cam downward, the catch holding all the connections against the power of the spring. The catch is released after the fraction of a revolution of the machine to allow the second step movement downward of the cam 6, 6' to take place, this release being effected by a cam 22 rotating with the take-up ring 23, it being secured thereto by the hangers 24. This cam as the take-up ring revolves (this moving with the needle cylinder as in ordinary practice) operates a lever 24' on a rock shaft 25, having its bearings in the frame bracket 19 and in the bracket 26, the upper end of this rock shaft having an arm 27 engaging a notch in a slide 28, suitably guided in the frame bracket and having a pin 29 which engages an arm 30 when the slide moves toward the right in Fig. 1. This arm 30 is on a rock shaft 31 journaled in the fixed base plate of the machine, and which forms the pivotal mounting for the catch. The catch is now moved away from the controlling pin 20 by the mechanism just described, allowing the spring 18 to move the lever 16, the roller of said lever being still opposite the space 17* of the pattern wheel, and thus the lever through the rod 14, ring 13 and rods 12 will operate all of the step cams 6, 6' all the way down to put the cylinder needles out of operation at these points for weltting on the dial at the feeds *b*. The catch 21 is, of course, operated at every revolution of the machine, and it is only when the pattern wheel presents its space 17* does it have any effect, as at other times the cam 6, 6' is held up by the pattern wheel acting through the lever and rods described. By controlling the step-by-step cam both by the pattern wheel and the cam 22, through the catch 21, a small measuring device, whether it be a wheel or a chain, may be used. The measuring device for the

pattern mechanism here shown is the chain 33'. The slide 28 is used for operating the pattern wheel 17, it being provided with a pawl 32 engaging a ratchet wheel 33 fixed on the shaft of the pattern wheel. The measuring chain 33' passes over a wheel or drum 33'' loose on the shaft of the pattern wheel, this chain determining when the pawl will engage the ratchet wheel 33. The 10 chain wheel is combined or formed with ratchet teeth 33* engaged by a pawl 32* on the slide 28, which pawls the chain around. This chain has high and low links, Fig. 2, to control the engagement of the pawl 32 with the ratchet 33 of the pattern wheel. We describe the measuring means only generally, as other forms and arrangements may be used. The rock shaft 25 is moved in opposition to the cam 22 by a spring 34, 20 and the spring gives the slide its return movement to the right, after operating the pattern wheel ratchet, for operating the catch 21. The catch 21 is also pressed by a spring 35 surrounding its rock shaft or 25 pivot pin tending to move it into position to hold the cams 6, 6', in intermediate position. The catch 21 may be otherwise operated than by the same cam which operates the pawl slide, for instance by a cam on 30 any revolving part of the machine, as a cam under or adjacent the needle cylinder. The wing cams 1' are operated automatically for weltting on the cylinder needles by links 36 on top of the dial cap, screws 35 from which links pass through slots of the cap into the wing cams and through slots 37 in the ring 13 into a lower ring 13' located immediately below the ring 13, Fig. 6. This lower ring is operated from a pattern 40 lever 38 through a rod 39, Fig. 1, connected with one of the screws which pivotally connects the link 36 of the wing cam to the ring 13'. The pattern lever is controlled by a pattern wheel 38' and a spring 38* in a manner similar to the lever 16, the pattern wheel being fixed on the same shaft as the pattern wheel 17.

When the welt is to be formed, the cam 6, 6' is dropped all the way down as above described, and in order to draw a longer stitch by the dial needles while they are forming their wall of the welt we employ adjustable blocks 40' on the ring 13 which come against levers 41 pivoted to the dial cap and having connection with the dial stitch cam 8' by pins 42 in the levers passing through slots 43 of the dial cap to bear on the outside edges of the stitch cams, so that when the ring 13 is moved to drop the cams 6, 6' all the way down, the stitch cams 8' will be adjusted inwardly to draw a longer stitch. Thus at the same time that the cylinder needles are thrown out of operation, at this feed, the dial cam is adjusted to draw a 65 longer stitch for the welt. The clearing

course cams 3, 4, are operated from a ring 44 encircling the head, said ring having inclines thereon 44' which raise posts 45 movable in brackets 46 attached to the cam cylinder, the posts 45 being connected by pins 70 47 with the posts 3* of the clearing course cams. This ring is operated through a rod 48 from a pattern lever 49 which has two arms 49', 49'', the former being operated from a pattern wheel 50 and the latter from a pattern wheel 51, so that the lever 49 is operated positively in both directions, and the ring may, through this pattern mechanism, be made to occupy four positions, i. e., for plain rib knitting, slackening on all feeds, 80 slackening on alternate feeds, and for the clearing course, it being understood that the stitch cams of the cylinder are adjusted by cams on the ring 44 in a manner similar to that disclosed in Letters Patent of the 85 United States granted to George L. Ballard, #391,809, June 30, 1908. The center rings 13, 13', may have three positions for plain rib knitting, welt, and tuck. The cams of the dial are attached in part to the main part 90 or hub of the dial cap, and in part to the removable sections thereof. The main hub part 51 of the dial cap is fixed to the dial post, and the removable dial cap sections 52 are secured by screws to a shouldered portion of this main hub part. The wing guard and dial stitch cams are mounted on the removable dial cap sections, one of these guard cams being shown at 53 in Fig. 6, whereas the other cams, i. e., in the present case the 100 tucking cam 54, is attached to the hub portion. This cam remains a fixture on the hub of the dial cap when its corresponding section and complementary cam is removed, and by this the needles can be controlled as 105 to their position for receiving the cams when the dial sections are again attached to the dial cap, as the edge of this cam will enable the needles to be properly positioned by simply pushing them inwardly. Further, these cams or cam portions may be made of thinner steel plate than were they secured to the removable section and were of sufficient thickness to reach to the level shown. It will be seen further that the 110 tucking cam 54 rests over the base of the wing cam and past the pivot thereof and into the mouth of the cam, and by this construction the needles will be prevented from 115 tipping back out of place through the opening usually present between the pivoted end of the wing cam and the adjacent fixed cam. This opening indicated at 55 is now closed against the inward movement radially of the needles because it is covered by the projecting portion 56 of the tucking cam. 120

Some of the parts shown in Fig. 1 have been omitted from Fig. 2 for clearness of illustration, and in Fig. 1 we have shown in dotted lines only the advancing and stitch 130

cams of the dial, having omitted the guard and tucking cams, which, however, are clearly shown in Fig. 4.

The brushes 4¹ are automatically thrown out of position over the needles, so as to save wear on the brushes when they are not needed, and we have illustrated means for doing this in connection with only one of the brushes, similar means being used with the other brushes in practice. This means consists of a lever 56 pivoted to the dial cap and operated by a pin 57 extending from the lower ring 13' up through a slot in the upper ring, so that when this lower ring is moved to adjust the wing cams of the dial the brushes will be moved out of operative position.

The pattern mechanism may be widely varied in construction, but in the particular form shown it is, in its general features, like that shown in the United States patent of McMichael, and Wildman, #508,965, November 21, 1893. The fabric produced is like that disclosed in our prior patent above noted.

We claim as our invention:

1. In combination in a rib knitting machine, a needle cylinder and dial, cylinder and dial cams, rings movable circumferentially of the dial, pattern mechanism on the fixed frame for operating the rings, connections from one ring extending through the dial cap to operate the dial cams, connections from the other ring for operating the cylinder cams, including rock shafts on the fixed cam ring connected with the cams, and rods connecting the rock shafts with said ring, substantially as described.

2. In combination in a rib knitting machine for making tubular welts, a rotary cylinder and dial, advancing and stitch cams for the cylinder and dial needles, a clearing course cam for the cylinder needles, rings extending circumferentially of the dial, connections from said rings to the advancing cams of the cylinder and dial, a circumferentially movable ring for operating the clearing course cam, and pattern mechanism for operating the rings, substantially as described.

3. In combination in a rib knitting machine for making tubular welts, a rotary cylinder and dial, advancing and stitch cams for the cylinder and dial needles, a clearing course cam for the cylinder needles, rings extending circumferentially of the dial, connections from said rings to the advancing cams of the cylinder and dial, a circumferentially movable ring for operating the clearing course cam, and pattern mechanism for operating the rings, said last mentioned ring adjusting also a stitch cam of the cylinder, substantially as described.

4. In combination in a circular rib knitting machine for making tubular welts, a

plurality of feeds, adjustable advancing cams of the dial alternating in position with adjustable advancing cams of the cylinder and each adjustable advancing cam being arranged adjacent the fixed advancing cam of the opposite set, pattern mechanism, rings on the dial, connections from the pattern mechanism for operating the rings, connections between one of the rings and the adjustable advancing cams of the dial, connections between the other ring and the adjustable advancing cams of the cylinder, stitch cams for the dial and cylinder, and a connection between alternate stitch cams of the dial and the ring which operates the advancing cams of the cylinder, substantially as described.

5. In combination in a rib knitting machine, a rotary needle cylinder and dial, dial cams, cylinder cams, the latter including an advancing cam movable step by step downward to be put out of operation, pattern mechanism for giving the cam its first step movement downward, a catch for arresting the cam, and a member rotating with the machine for releasing the catch for the further downward movement of the cam, substantially as described.

6. In combination in a rib knitting machine, a rotary cylinder and dial, cylinder and dial cams including an advancing cam movable step by step to be placed out of operation, a catch for controlling the movement of the cam, pattern mechanism with connection to the cam for giving it its first step movement, and a cam mounted on a rotating part of the machine for controlling the catch to effect the second step movement of the cam, substantially as described.

7. In combination in a rib knitting machine, a rotary cylinder and dial, cylinder and dial cams, including an advancing cam movable step by step, connections for operating the cams, a spring for operating the connections, pattern mechanism for controlling the spring and said connections, to give the cams their first step movement, a catch for controlling the said connections, and a cam member mounted on a rotating part of the machine for controlling the catch to effect the second step movement of the cam, substantially as described.

8. In combination in a rib knitting machine with a rotary cylinder and dial, and cylinder and dial cams, including a step by step cam for placing the cylinder needles out of operation, pattern mechanism, a slide for operating the pattern mechanism, connections between the pattern mechanism and the step by step cam, a catch for controlling the said connections, a member carried by a rotary part of the machine for operating the slide, said slide, in turn, controlling the catch, substantially as described.

9. In combination in a rib knitting ma-

- chine, a plurality of feeds, a plurality of step by step adjustable cams for the cylinder needles, a catch with connections to all of the said cams for retaining them in their intermediate positions, and means for controlling the catch, substantially as described.
10. In combination in a rib knitting machine for making welts, the cylinder and dial needles, dial cams, the cylinder cams including a plurality of advancing cams adjustable step by step, a ring connected with the step by step cams, a catch for controlling the position of the ring, pattern mechanism for operating the ring, and a member rotating with the machine for controlling the catch, substantially as described.
11. In combination in a rib knitting machine for making tubular welts, the cylinder and dial cams including a plurality of advancing cams for the cylinder needles, a ring with connections to the said cams, including rock shafts, pattern mechanism con-
- nected to the ring, a catch for controlling one of the rock shafts, and thereby controlling all of the cams through the ring, and means for controlling the catch, substantially as described. 25
12. In combination with a dial plate, a grooved wing cam pivotally supported thereon, and a cam adjacent the wing cam and forming the inner wall of the cam way, said cam reaching over lower face of the wing cam at its pivoted end and extending into the mouth of the groove thereof to close the cam way against displacement of the needles radially inward, substantially as described. 30
13. In combination with a dial plate, a grooved wing cam pivotally supported thereon, and a cam adjacent the wing cam and forming the inner wall of the cam way, said cam reaching over lower face of the wing cam at its pivoted end and extending into the mouth of the groove thereof to close the cam way against displacement of the needles radially inward, substantially as described. 35

In testimony whereof, we affix our signatures in presence of two witnesses.
